UNITED STATES PATENT OFFICE.

ALFRED J. STECKER, OF DETROIT, MICHIGAN, ASSIGNOR TO FRED WARDELL, OF DETROIT, MICHIGAN.

DESIGN FOR A CASING FOR PNEUMATIC CLEANING-MACHINES.

40,982.

Specification for Design.

Patented Nov. 8, 1910.

Application filed April 8, 1910. Serial No. 554,298. Term of patent 7 years.

To all whom it may concern:

Be it known that I, ALFRED J. STECKER, a citizen of the United States, residing at Detroit, in the county of Wayne and State of Michigan, have invented a new, original, and ornamental Design for a Casing for a Pneumatic Cleaning-Machine, of which the following is a specification, reference being had to the accompanying drawing, forming a part thereof.

Figure 1 is a perspective view of a casing

for a pneumatic cleaning machine, showing my new design. Fig. 2 is a side elevation thereof, and Fig. 3 is a front elevation.

I claim—

The ornamental design for a casing for a pneumatic cleaning machine, as shown.

ALFRED J. STECKER.
